Primary Examiner — David G Muller*(74) Attorney, Agent, or Firm* — Levenfeld Pearlstein, LLC(57) **CLAIM**

The ornamental design for a convex insert for ostomy appliance, as shown and described.

DESCRIPTION

FIG. 1 is a top view of a convex insert for ostomy appliance embodying our new design;

FIG. 2 is a bottom view thereof;

FIG. 3 is a front view thereof;

FIG. 4 is a rear view thereof;

FIG. 5 is a side view thereof as seen from the right-hand side of FIG. 3;

FIG. 6 is a side view thereof as seen from the left-hand side of FIG. 3;

FIG. 7 is a top perspective view thereof; and,

FIG. 8 is a bottom perspective view thereof.

Portions of the convex insert for ostomy appliance shown in dashed lines in FIGS. 1-8 form no part of the claimed design.

1 Claim, 8 Drawing Sheets(56)
